UNITED STATES PATENT OFFICE.

CARL WIGTEL, OF BROOKLYN, NEW YORK, ASSIGNOR TO FRANCIS H. STILLMAN, OF BROOKLYN, NEW YORK.

HYDRAULIC RAIL-BONDING TOOL.

SPECIFICATION forming part of Letters Patent No. 763,581, dated June 28, 1904.

Application filed December 20, 1899. Serial No. 740,973. (No model.)

To all whom it may concern:

Be it known that I, CARL WIGTEL, a citizen of the United States, and a resident of the borough of Brooklyn, in the county of Kings, 5 in the city and State of New York, have invented a certain new and useful Improvement in Hydraulic Rail - Bonding Tools, of which the following is a full, clear, and exact description, reference being made to the accompanying drawings, forming part of this specification.

This invention relates to improvements in hydraulic tools which comprise a ram in the lower part of the body, the face of the ram 15 being upward and a jaw projecting over the ram; and the invention consists of a hydraulic tool and mechanism appertaining thereto constructed or constructed and combined as herein described and claimed.

On the accompanying sheets of drawings, Figure 1 is side elevation of a riveting-tool and supplemental mechanism, a vertical section of a support on which they are mounted, and a fragment of a cross-section of an electric railway, the tool being shown hung in a manhole of the railway ready to act on a bond-rivet in one of the conductor-rails; Fig. 2, a front elevation of the tool and supplemental mechanism and parts of the support and fragments of a longitudinal section of the railway crossing the manhole; Fig. 3, a sectional detail of certain devices attached to the top of the head of the tool, and Fig. 4 a side elevation of the head and body of the tool and a 35 vertical section of a tool-base and rail-support.

Similar reference-numerals designate like parts in different views.

The main object of this invention is to produce a hydraulic tool so constructed and combined with supplemental mechanism as to render it fit for use in manholes of an electric railway in installing rail-bonds in conductor-rails fixed in a conduit below the level of the 40 track. The interior of a manhole being small and the yokes, slot-rails, insulators, supporting-brackets of the conductor-rails, and other parts of the underground structure obstructing access to the conductor - rails except

through small spaces, a tool to be fit for the 50 use contemplated must have various peculiarities in form and arrangement of parts and should be capable of being operated from above the track, where there is plenty of room.

Although the particular tool shown is a 55 bond-riveting tool, yet the main features of the invention might be embodied in a press comprising instead of a rivet-set a device of another form or in a punching-tool, a punch being substituted for the rivet-set and a die 60 being fixed in a hole in the jaw overhanging the ram, as appears by an application for a patent for a hydraulic punch filed May 19, 1899, and bearing the serial number 717,452, and the invention is accordingly claimed with 65 the intention of securing it not only in the precise form shown, but in all mere modifications thereof.

The body of the tool is a steel casting composed of the trunk 1, the ram-cylinder 10, 70 formed on and in front of the lower part of the trunk, the jaw 11, projecting over the ram-cylinder, and the stock 12, formed on the rear part of the top of the trunk, the stock 12 and the ram-cylinder being respectively at the top 75 and bottom of the body and their axes being parallel, that of the ram-cylinder being in front of the other. The upper part of the stock 12 is hollow, and a fluid-passage extends from the bottom of the recess therein to the 80 interior of the ram-cylinder below the ram, this passage being formed by drilling intersecting holes 13 and 13' in the body, as is indicated by dotted lines in Fig. 1. The outer end of the hole 13' is closed by a screw-plug. 85 The rivet-set 14, fixed on the ram, projects far enough from the ram to insure its proper action on the bond-rivet, although the face of the ram is not raised quite to the rail. A handle 15 is attached to the back of the tool. 90

On the body is a head 2, which is screwed into the stock 12 and which contains a pump that is actuated by a handle-bar inserted in the socket 2'. The axis of the head coincides with the prolonged axis of the stock, and the 95 interior of the head communicates with the passage 13 13'. The top of the head is a screw-plug 20, having the form shown in Fig.

3, its stem being composed of the plain cylindrical section 21, the smaller threaded section 22, and the still smaller plain section 23. On the section 21 of the stem is a loose collar 25, 5 on which is a slotted projection 25', containing a hole in which fits a pin 26. This collar is confined on the stem of the plug by means of a washer 21' and a nut 22'. The weights of the several parts of the tool are so proportioned that the center of gravity of the tool, which is below the collar 25, lies in the median plane of the tool or the plane containing the axes of the head and ram and between those axes, its distance in front of the axis of 10 the head being equal to that of the axis of the pin 26 from the axis of the head. A hook 27 is pivoted on the pin 26 in the slot in the projection 25', the hook being properly formed and being at a proper distance above 15 the jaw 11 to engage a slot-rail when the tool is in a proper position to act on a conductor-rail in the conduit, as appears by Fig. 1.

The support from which the tool hangs consists of two bars 3 of wrought iron or steel, 20 bent as shown by Figs. 1 and 2 and secured together by pins 30, on which are separators like the sleeve 31, (shown in Fig. 1,) the bars being held by the pins in contact with the ends of the separators. The support is longer 25 than the distance across a manhole and stands with two of its feet 3' on one side and its other two feet on the opposite side of the manhole, in which the tool hangs. Blocks 32 are fastened between the bars 3 by pins 32', and 30 to these blocks handles 33 are pivoted.

A truck composed of a block 4, on which are axles 4', and of grooved wheels 40 on the axles, is mounted on the support, which provides a track along which the truck may be 35 easily moved. Through an unthreaded hole in the block 4 and between the bars 3 of the support passes a screw 5, to which is attached a crank 50, the screw being loose in the block and having a head or fixed collar 5', which 40 rests on the top of the block and by which the screw hangs. On the lower part of the screw is a yoke 51, with which the screw engages in a screw-threaded hole extending through the top of the yoke. This yoke is pivoted to the 45 projection 25' on the head of the tool by the pin 26 passing through the sides 51' of the yoke, the projection and rear end of the hook 27 being within the yoke.

The tool naturally assumes an upright position under the action of its center of gravity, with the axes of the head and ram vertical when it hangs from the support with its median plane at right angles to the axis of the pin 26, since it swings freely on the axes 55 of the pin 26 and the axles 4', which axes are above the center of gravity and intersect a straight line drawn through it parallel to the axes of the head and ram, and the tool may be turned on the axis of the head, the stem of 60 the plug 20 turning in the collar 25, and may

be raised and lowered on the screw. The tool is lowered into the manhole by the handles 33 of the support, and then the hook 27 is engaged with the slot-rail 6, and the tool is further adjusted, if necessary, by moving the 70 truck and turning the tool on the axis of the head by the handle 15, the screw being so adjusted that the ram and jaw 11 pass under the base of the slot-rail and the jaw passes over and the rivet-set under the bond-rivet in the 75 conductor-rail 7. The adjustment of the tool is completed by turning the screw and lowering the tool until the jaw is in firm contact with the head of the bond-rivet. The tool is lowered into and adjusted in the manhole from 80 above the manhole. It is also operated from above the manhole.

The bond-rivet is upset by the action of the ram and rivet-set thereon, the ram being forced upward by pumping fluid from the 85 head into the ram-cylinder through the passage 13 13'. The ram is then depressed by drawing the head and body of the tool upward by means of the screw 5, the ram-cylinder being thus raised on the ram, and afterward lowering the tool.

The hook 27 not only serves as a gage to facilitate the adjustment of the tool as described, but constitutes also a tie that prevents the top 95 of the tool from being pulled backward in the operation of the tool by the force exerted on the handle-bar which actuates the pump and which extends upward and backward over the manhole.

The tool-base and rail-support shown in Fig. 100 4 is used with the tool when rail-bonds are installed or partly installed in the conductor-rails before these rails are put into the conduit. This device is composed of a flat block 8, of wood or metal, on which are a collar 80, 105 a post 81, and rail-rests on opposite sides of the collar, each consisting of a bent piece of iron 82, fastened at its ends to the block. The collar fits around the bottom of the ram-cylinder, and the post helps to support the tool, as 110 shown, there being in the collar a set-screw 80' and in the post a pin 81, that enters a hole in the body of the tool. The rail is supported by the rail-rests, as appears by the drawings, during the operation of the tool on the rail-bond. 115

Having thus described my invention, what I claim as new, and desire to secure by Letters Patent, is—

1. A hydraulic tool comprising the combination of: a fixed jaw having on its under side a seat to fit the head of a rivet; a ram underneath said fixed jaw, the face of the ram being upward; a rivet-set on the ram to coact with said fixed jaw in upsetting rivets; and a head above the fixed jaw, the interior of the head being connected with that of the ram-cylinder below the ram by a fluid-passage; substantially as described. 120

2. A hydraulic tool comprising the combina- 125

tion of: a fixed jaw; a ram underneath said fixed jaw, the face of the ram being upward; devices on said fixed jaw and ram to coact on the work; and a head above the fixed jaw, the 5 interior of the head being connected with that of the ram-cylinder below the ram by a fluid-passage; the axes of the ram and head being parallel to each other and vertical when the tool is upright and the axis of the ram then being in front of that of the head; substantially as described.

3. A hydraulic tool comprising the combination of: a fixed jaw; a ram underneath said fixed jaw, the face of the ram being upward; devices on the ram and fixed jaw to coact on the work; a head above the fixed jaw, the interior of the head being connected with that of the ram-cylinder below the ram by a fluid-passage; means to hang the tool in an upright 15 position on an axis which is transverse to that of the head; and a device on the tool above the fixed jaw to engage, and connect the tool, with a fixed object; substantially as described.

4. A hydraulic tool comprising the combination of: a fixed jaw; a ram underneath said fixed jaw, the face of the ram being upward; devices on the ram and fixed jaw to coact on the work; a head above the fixed jaw, the interior of the head being connected with that of the 25 ram-cylinder below the ram by a fluid-passage; a projection on the head, extending over the center of gravity of the tool; means to hang the tool in an upright position by said projection; and a device attached to the projection 30 to engage, and connect the tool, with a fixed object; substantially as described.

5. A hydraulic tool comprising the combination of: a fixed jaw; a ram underneath said fixed jaw, the face of the ram being upward; devices on the ram and fixed jaw to coact on the work; a head above the fixed jaw, the interior of the head being connected with that of the ram-cylinder below the ram by a fluid-passage; means to hang the tool in an upright 40 position, the tool being movable about a vertical axis; and a device on the tool above the fixed jaw to engage, and connect the tool, with a fixed object; substantially as described.

6. A hydraulic tool comprising: a ram in the lower part of the body, the face of the ram being upward; a jaw projecting over the ram; devices on the ram and jaw to coact on the work; a head on the upper part of the body, the interior of the head being connected with that of the ram-cylinder below the ram by a fluid-passage; a screw which extends downward from a support and on which the tool hangs; and a device on the tool above said jaw to engage, and connect the tool, with a fixed object; 55 substantially as described.

7. A hydraulic tool comprising a head from which fluid is forced into the ram-cylinder to actuate the ram, the head having on it a projection extending in front of the axis of the head and directly above the center of

gravity of the tool, in combination with a screw on which the tool hangs in an upright position, the screw being supported above and connected with said projection, substantially as described.

8. A hydraulic tool comprising a head from which fluid is forced into the ram-cylinder to actuate the ram, the head having on it a projection extending in front of the axis of the head and directly over the center of gravity of the tool, in combination with: a screw on which the tool hangs, the screw being supported above and connected with said projection; and a hook pivoted to said projection; substantially as described.

9. A hydraulic tool comprising a ram in the lower part, and a head on the upper part, of the body, the axes of the head and ram being parallel to each other, and the center of gravity of the tool being between them, in 85 combination with means, connected with the tool in front of the head, to hang the tool in an upright position, substantially as described.

10. A hydraulic tool comprising: a ram in the lower part of the body, the face of the 90 ram being upward; a jaw projecting over the ram; a head on the upper part of the body; and a gage attached to the head near the top of the tool; the gage being at a proper distance above the jaw to engage a slot-rail of a railway when the tool is in a proper position to act on a conductor-rail in the conduit below the slot-rail; substantially as described.

11. A hydraulic tool comprising: a ram in the lower part of the body, the face of the 100 ram being upward; a jaw projecting over the ram; a head on the upper part of the body; and a hook attached to the head of the tool; the hook being at a proper distance above the jaw to extend over, and engage with the inner 105 edge of, a slot-rail of a railway, when the tool is in a proper position to act on a conductor-rail in a conduit below the slot-rail; substantially as described.

12. A hydraulic tool comprising a ram on the lower part of the body, the face of the ram being upward, and a fixed jaw on the body projecting over the ram, in combination with: a gage to facilitate the adjustment of the tool, said gage being connected with the tool above 115 the fixed jaw; and means to hang the tool from a support, with the axis of the ram vertical; substantially as described.

13. A hydraulic tool comprising a ram, a fixed jaw and a head containing a hand-operative pump, in combination with a loose collar mounted on the head, and with a gage attached to the collar, substantially as described.

14. A hydraulic tool comprising a ram, a fixed jaw and a head containing a hand-operative pump, in combination with a loose collar mounted on the head, and with a hook 125 pivoted to the collar, substantially as described.

15. A hydraulic tool comprising a ram, a 130

- fixed jaw and a head containing a hand-operative pump, in combination with a device on the tool for engaging a fixed object to counteract the tendency of the tool to tip under the action of the force exerted on the handle-bar of the pump contained in the head, substantially as described.
16. A hydraulic tool comprising a ram, a fixed jaw and a head containing a hand-operative pump, in combination with a loose collar mounted on the head, and with means connected with the collar for engaging a fixed object to counteract the tendency of the tool to tip under the action of the force exerted on the handle-bar of the pump contained in the head, substantially as described.
17. A hydraulic tool comprising a ram, a fixed jaw and a head containing a hand-operative pump, in combination with a loose collar mounted on the head, and with means for hanging the tool from a support by a connection secured to said collar, substantially as described.
18. A hydraulic tool comprising a ram, a fixed jaw and a head, in combination with: a loose collar mounted on the head; a yoke 51 pivoted to a projection on the collar; and a screw 5 hanging from a support and engaging with the yoke; substantially as described.
19. A hydraulic tool comprising a ram, a fixed jaw and a head, in combination with: a loose collar mounted on the head; a yoke 51 pivoted to a projection on the collar; a screw 5; a truck on which the screw hangs; and a support constituting a track on which the truck is mounted; substantially as described.
20. A hydraulic tool comprising a ram, a fixed jaw and a head, in combination with: a loose collar 25 mounted on the head; a hook 27 pivoted in the slot in the projection 25' of the collar; and means for hanging the tool from a support by a connection secured to said projection; substantially as described.
21. A rail-bonding tool in combination with: a screw on which the tool is suspended on an axis which intersects at right angles the prolonged axis of the screw; a track; and a truck mounted on the track; the truck comprising a block that turns on an axis, and the screw being secured to said block; substantially as described.
22. A rail-bonding tool in combination with: a yoke 51 in which the tool hangs on a horizontal axis; a screw 5 which engages with the yoke and whose axis intersects said horizontal axis at right angles; a truck comprising a block 4, and wheels 40 on the axles 4'; and a track on which the truck is mounted; the screw 5 extending through and hanging on the block 4; substantially as described.

CARL WIGTEL.

In presence of—

ANDREW P. HACHTMANN,
W. R. WILSON.
